UNITED STATES PATENT OFFICE

JAMES E. FOULKS, OF BRIGHTWATERS, NEW YORK, ASSIGNOR TO CLIMAX STATIONERY COMPANY, INC., OF NEW YORK, N. Y., A CORPORATION OF NEW YORK

METHOD OF BINDING SHEETS

Original application filed January 21, 1927, Serial No. 162,631. Divided and this application filed June 20, 1929. Serial No. 372,250.

This invention relates to the binding of loose sheets and particularly sheets of different sizes and is for subject-matter divided from my co-pending application filed 5 January 21, 1927, bearing Serial No. 162,631.

It is the object of the invention to provide an improved method of assembling and binding loose sheets into a sheet body and the mounting of the sheet body in a cover, and 10 to provide a method by which loose sheets may not only be more readily and easily bound, but in a less expensive and more efficient manner.

In carrying out the invention binders 15 comprising strips of laterally pliable and edgewise stiff and readily severable material are folded upon themselves with a loop arranged at the fold, although this is not absolutely essential, with the ends of the strip 20 extending in parallel and contiguous relation, an abutment in the form of a pin being engaged in the fold, or within said fold in a tubular member having a longitudinal slot for lateral engagement onto the binder 25 strip. The sheets to be bound are previously arranged adjacent to one edge with spaced 30 perforations conforming to the cross sectional shape of the binders, the binders being engaged in said perforations to assemble 35 the sheets thereon to form a sheet body with the loop arranged at the fold of the strips, or said loop engaged in the tubular member, abutting against one side of the sheet body the strips being of a length to 40 extend beyond the opposite side of the sheet body. The free ends of the binder strips at the opposite side of the sheet body are then severed to a predetermined length and each end folded upon itself when a longitudinal- 45 ly slotted tubular member is engaged thereon similar to the tubular member engaged upon the loop at the fold of the strip, and an abutment pin is then engaged in said tubular member to co-operate with the folded strip 50 ends to secure the tubular member thereon and retain the sheets assembled upon the binders. Should the sheets constituting the sheet body so bound be of different sizes the marginal portions of the sheet body are 55 trimmed and the bound sheets in such condi-

tion may be stored away for future reference. If desired, the sheet body may be mounted in a cover comprising a back with leaf sections connected thereto, said cover being arranged with aligned and spaced tubular members in the region of the juncture of the leaf sections and the back with which the tubular members on the binders of the sheet body are interlocked by inserting the bound sheet body between the leaf sections 55 and interengaging or interposing said tubular members in the spaces between and in line with the tubular members on the cover and then engaging pintles in the aligned tubular members, said tubular members being in 60 the nature of knuckles.

In the drawings accompanying and forming a part of this specification Figure 1 is an end elevational view of a binding body showing the arrangement of a bound sheet 70 body mounted therein.

Figure 2 is a cross sectional view on an enlarged scale taken on the line 2—2 of Figure 1 looking in the direction of the arrows.

Figure 3 is a fragmentary sectional view taken on the line 3—3 of Figure 1 looking in the direction of the arrows.

Figure 4 is a perspective view to show the mounting of the binders of the sheet body 8 on mounting plates arranged with spaced tubular members constituting a part of the cover.

Figure 5 is a fragmentary end view showing the leaf sections of the cover in open 85 position as well as the sheets of the sheet body to show the manner in which a spreading force of the sheets exerts a binding and clamping force upon the sheets of the sheet body.

Figure 6 is an end elevation of a binder with the tubular members engaged thereon to retain the sheets in assembled position on the binders.

Figure 7 is a perspective view of the strip 95 from which the binders are formed.

Figure 8 is a perspective view of the strip showing the same as arranged to form the binder.

Figure 9 is a fragmentary view of a sheet 100

showing an arrangement of a perforation therein.

Figure 10 is a perspective view of one of the tubular members or knuckles for engagement on the binders to retain the sheets of the sheet body assembled on the binders.

Figure 11 is a fragmentary perspective view showing the method of assembling the sheets on the binders; and

10 Figures 12 to 18, inclusive, are a series of views in perspective showing the successive steps of the method of folding the free ends of the binders preparatory to the engagement of a tubular member or knuckle thereon.

15 In the embodiment of the invention the sheets S are first arranged with spaced perforations 19 along one marginal portion. These perforations may be of any desired 20 number, four being in the arrangement of binding means illustrated. The sheets are bound together by binders engaged in the sheet perforations to assemble the sheets on the binders to form a sheet body.

25 The binders comprise a strip 23, as shown in Figure 7, of flat laterally pliable though edgewise stiff material, such as brass or copper, the strip being folded upon itself and arranged with a loop portion 24 at the fold, 30 the two folded portions 25 extending in contiguous parallel relation from the loop portion, as shown in Figure 8. The sheets are assembled on said binders as shown in Figure 11 with the loop portion abutting 35 against one side of the sheet body with the free ends extending beyond the side of the sheet body opposite to that against which the loop portion of the binders abuts. The free ends of the binders are severed, as by 40 a pair of shears, to a predetermined length extending from the said side of the sheet body. To assure the severing of the ends at the proper length a gauge member 26 is provided. This gauge member is constructed 45 of a sheet metal plate of rectangular shape with a central slot 27 cut into one end and terminating within the body of the plate with the opposite end of the plate arranged with a reduced portion 30. The plate is 50 folded upon itself so that the reduced portion 30 will overlie a portion of the slot 27, as shown in Figures 12, 13 and 14. The folded portion is bent to extend at a right angle to the body, as at 28. In practice the 55 gauge is engaged flat upon the sheet body with the projecting ends of the binder engaged in the slot 27 in abutting relation to the end of the reduced portion 30, the ends of the binder being severed at a predetermined point so that the portion of the binder 60 ends extending from the top of the sheet body is equal in length to the height of the bent portion 28 of the gauge. The extended ends are then spread or bent laterally 65 and contiguously of the legs formed by the

slot 27 of the gauge member at opposite sides of the said slot, as at *a* in Figure 13. The gauge member is then moved forward so that the reduced portion 30, which is in the nature of a projection or tongue, will overlie and be contiguous to the spread ends of the binder. The ends are then bent inwardly upon themselves over the projection or tongue 30, as at *b* in Figure 14, when the reduced portion of the gauge member is withdrawn from engagement within the bent ends and they are forced together by a suitable tool, such as a hammer, thereby forming an abutment against the side of the sheet body, as at *c* in Figure 15.

To retain the sheet body in assembled position on the binders, knuckles 31 in the form of tubular members having a slot 32 cut into one end and terminating adjacent the opposite end, are engaged laterally upon the ends of the binders with the loop portion 24 within one knuckle and the folded ends within the other knuckle, as shown in Figure 6. The size of the knuckles is such that they can be readily slid over the loop portion of the binders. In order that the knuckles may be engaged over the folded extended end of the binder the folded portions *c* are bent up to slightly curved form in cross section by any suitable means, as shown at *d* in Figure 16, when one end portion is folded or pinched together to permit of inserting the same into the slotted end of a tubular member or knuckle, as at *e* in Figure 17, and the material being pliable as force is applied to the knuckle to slide it onto the folded end of a binder the material will readily form itself for engagement in the knuckle. After the knuckle has been engaged upon the folded ends of the binder an abutment is engaged in the knuckle in interposed relation to said folded ends, said abutment being in the form of a pointed pintle 37' shaping the folded binder ends as shown at *f* in Figure 13 facilitating the ready removal and engagement of the knuckle thereon. A similar pintle is engaged in the loop 24 of the binder within the knuckle. These abutments firmly clamp the portions of the binder within the knuckles and secure the latter upon the binders and prevent any strain which may be applied to the binders, as by moving the bound sheets to open position and applying a force upon the open and spread sheets, from pulling the binders from the knuckles. While it is not absolutely essential to apply a knuckle member upon the loop of the binders, it is preferable as it adds strength to the binder.

The method of binding as described is particularly adapted for the binding of loose sheets of different sizes and after the sheets have been assembled and secured upon the binders into a sheet body the irregular

edges of the sheet body are trimmed or cut off in an ordinary paper cutter and thus squaring all of the edges. The bound sheet body in such form may be filed away for future reference.

Should it be desired the sheet body bound on the binders as described may be mounted or bound in a binding body or cover as shown in Figure 1. For this purpose there is provided a binding body or cover comprising a back 20 of curved form in cross section and a pair of cover sections or leaves 21 movably connected to the back, as at 22, in the present instance by a covering material, such as canvas or buckram, for the back and cover leaves, the back and cover leaves being constructed of a rigid material, such as cardboard or binder's board.

To mount the sheet body assembled on the binders in the cover the latter is arranged with two rows of spaced and aligned knuckles or tubular members in the region of the juncture of the cover leaves and the back with which the knuckle members on the binders are adapted to be interlocked. For this purpose there is provided a pair of plates 33 having portions stamped therefrom to form recesses 34 extending inward from one longitudinal edge and the plate is arranged with tongue 35 the outer marginal portion of which is rolled to form the knuckles, as shown at 36. The plates so formed are provided with perforations 37 and connected to the back with the knuckles to extend longitudinally and forwardly of the longitudinal marginal portions of the back, as clearly shown in Figure 1, by means of rivets engaged in the plate perforations and correspondingly arranged perforations in the back. In this arrangement the pintles or abutments engaged within the binder knuckles also serve to mount and secure the bound sheet body in the cover. In the mounting of the sheet body in the cover all that is necessary is to insert the sheet body between the cover leaves and the knuckles 31 interengaged with the plate knuckles 36 by positioning the knuckles 31 in the recesses 34 in aligned relation with the plate knuckles, when the pintle 37 in the form of a rod is inserted into the aligned openings in the knuckles, and in effect provides a hinged connection between the bound sheet body and the cover. By this arrangement as the cover leaves are moved to open position, as shown in Figure 5, the sheets or leaves of the sheet body spread to position to lie contiguous to the cover and substantially flat and any pressure which may be applied to the opposite spread portions of the sheet body, or the compression force with which the knuckle members hold the sheets of the sheet body upon the binders, is increased, this being due to the slight flexing of the binding in the direction of the

strain and the drawing of the sheets more firmly together through the flexing pull on the binders. The forces of said pull is applied upon the sheets through the knuckle members on the binders and the knuckle formed on the plates carried by the back of the cover.

The bound sheet body may be removably mounted in the binding body by making the pintle rod 37' of such length so that one end will project from the knuckle plate 36 at an end of the plate. However, to prevent the ready removal of the sheet body from the cover the knuckle at the one end of the plates 33 is arranged as a blind knuckle, as shown at 39 Figure 3, and the pintle rods are of less length than the knuckle carrying plates, and as said rods are engaged in the knuckles they are driven therein by a suitable implement so that the one end will be in engagement with the obstruction in the end plate knuckle, and the other end of the pintle will terminate within the plate knuckle at the opposite end of the plate, as shown at 40 in Figure 2.

While I have illustrated one embodiment of a method of binding loose leaf sheets in a sheet body and the mounting of the bound sheet body in a cover it will be obvious that various modifications may be made in the construction and arrangement of parts without departing from the scope of the invention and that portions of the invention may be used without others and come within the scope of the invention.

Having thus described my invention, I claim:

1. The method of binding loose sheets, which consists in perforating the sheets adjacent to one edge thereof, providing laterally pliable and edgewise stiff strips folded upon themselves, and engaging said strips in the sheet perforations to assemble the sheets thereon into a sheet body with the ends of the strip extending beyond the sides of the assembled sheet body, engaging slotted tubular members laterally onto the ends of the strips, and inserting pins in the tubular members to engage within the fold and between the opposite ends of the strips to secure the tubular members on the ends of the strips and retain the sheet body assembled.

2. The method of binding loose sheets, which consists in perforating the sheets adjacent to one edge thereof, providing laterally pliable and edgewise stiff strips folded upon themselves with a loop arranged at the fold and the ends extending in parallel relation, engaging said folded strips into the sheet perforations to assemble the sheets thereon in a sheet body with the looped portion of the strip at one side of the sheet body and the free ends extending from the opposite side of the sheet body, folding said free ends upon themselves, en-

gaging slotted tubular members laterally on the looped portion and folded ends of the strips, and inserting pintles in the tubular members engaged between and within the 5 loop of the strips and in the other tubular members to co-operate with the folded ends therein to secure the tubular members on the strips and retain the sheet body assembled.

10 3. The method of binding loose sheets, which consists in perforating the sheet adjacent to one edge thereof, assembling the sheets into a sheet body upon pliable strips engaged in the sheet perforations with the 15 opposite end portions of the strips extending beyond the opposite sides of the body, severing the extending ends at a predetermined distance from the sides of the sheet body, folding said severed ends upon themselves, engaging slotted tubular members 20 laterally on the folded ends of the strips, and inserting means in said tubular members to co-operate with the folded ends of the strips in said members to secure the 25 members upon the strips.

4. The method of binding loose sheets, which consists in perforating the sheets adjacent to one edge thereof, assembling the sheets into a sheet body upon pliable strips 30 engaged in the sheet perforations with the opposite end portions of the strips extending beyond the opposite sides of the sheet body, severing the extending ends at a predetermined distance from the sides of the 35 sheet body, bending the severed ends contiguous to the sheet body, folding portions of the bent ends upon themselves, engaging slotted tubular members laterally on the folded ends of the strips, and inserting 40 means in said tubular members to co-operate with the folded ends of the strips in said members to secure the members upon the strips.

5. The method of binding loose sheets, 45 which consist in perforating the sheets adjacent to one edge thereof, assembling the sheets into a sheet body upon pliable strips engaged in the sheet perforations with the opposite end portions extending beyond the 50 opposite sides of the sheet body, severing the extending ends at a predetermined distance from the sides of the sheet body, bending the severed ends contiguous to the sheet body, folding portions of the bent ends upon themselves, curving the folded portions of the 55 ends toward each other, engaging slotted tubular members laterally on the curved ends of the strips, and inserting means in said tubular members to co-operate with the 60 curved ends of the strips in said members to secure the members upon the strips.

6. The method of binding loose sheets, 65 which consists in perforating the sheets adjacent one edge thereof, assembling the sheets into a sheet body upon juxtaposed

pliable strips of an edgewise stiff and laterally pliable material engaged in the sheet perforations with the opposite end portions of the strips extending beyond the opposite sides of the sheet body, and drawing the 70 sheets of the sheet body into and retaining them in compact assembled relation by means engaged between and upon the ends of the strips extended beyond the opposite sides of the sheet body.

Signed at the city of New York, in the county of New York, and State of New York, this 10th day of June, 1929.
